UNITED STATES PATENT OFFICE.

BURT N. PIERCE, OF BOSTON, MASSACHUSETTS.

CARBURETOR.

1,403,706.

Specification of Letters Patent. Patented Jan. 17, 1922.

Application filed March 2, 1917. Serial No. 152,028.

To all whom it may concern:

Be it known that I, BURT N. PIERCE, a citizen of the United States, residing at Boston, in the county of Suffolk and State of Massachusetts, have invented certain new and useful Improvements in Carburetors, of which the following is a specification, reference being had therein to the accompanying drawings.

10 This invention relates to certain new and useful improvements in carburetors, the object being to provide a carburetor with a primary Venturi tube having a nozzle arranged therein, and a conical tube having 15 a nozzle disposed adjacent thereto, said conical tube being disposed to deliver into the main air passage or preliminary mixing chamber additional fuel when the suction controlled valve is raised on the increased 20 speed of the motor, said valve providing means for delivering into the main mixing chamber an additional supply of air so that the main volume of explosive mixture will be followed by an annular volume of air in 25 order to produce a thorough mixture within the mixing chamber so that an explosive charge will be produced which will explode readily within the cylinders of the engine.

Another object of my invention is to provide 30 a carburetor having a mixing chamber which communicates with the primary Venturi tube through a hollow suction-controlled valve which valve normally closes the auxiliary air supply so that the auxiliary 35 air will not be delivered to the mixing chamber until the suction created therein is increased by the speed of the motor.

Another and further object of the invention 40 is to provide a carburetor with a priming jet disposed above the throttle valve having a needle valve control and provided with a fuel conduit extending to the bowl of the carburetor in order to allow pure fuel 45 to be drawn directly from the bowl to the throttle chamber of the carburetor which enables a cold motor to be started readily.

Another and further object of the invention 50 is to provide a carburetor which is so constructed that when the speed of the motor is increased beyond a predetermined speed the high speed jet will be brought into operation so as to deliver to the preliminary mixing chamber additional fuel and at the same time an additional air supply is provided 55 so as to produce the proper mixture of air and gas at all speeds of the engine.

Another object of my invention is to provide a carburetor which is exceedingly simple and cheap in construction, the same being formed of two castings bolted together 60 in order to allow the same to be readily assembled or taken apart to reach the interior of the same for repairing or adjusting any of the parts.

Another and still further object of the invention is to provide novel means for adjusting the position of the suction-controlled floating valve in respect to its seat.

Other and further objects and advantages of the invention will be hereinafter set forth 70 and the novel features thereof defined by the appended claims.

In the drawings,

Figure 1 is a longitudinal vertical section through the carburetor;

Figure 2 is a perspective view of the carburetor;

Figure 3 is a vertical transverse section through the float and fuel chamber showing the secondary air inlet tube and the control 30 for the priming jet.

Figure 4 is a perspective view of the means for adjusting and holding the suction-controlled valve in position in respect to its seat.

Like numerals of reference refer to like parts in the several figures of the drawing.

In carrying out my invention I construct a carburetor of superposed castings comprising a base section 1 and a top section 2 provided with laterally extending abutting annular flanges secured together by bolts 3. The base section 1 is provided with a vertically disposed carbureting passage 4 having a lateral air inlet 5 at its lower end, said carbureting passage 4 terminating in a conical portion 6 at its upper end forming a conical valve seat 7 for the purpose hereinafter fully described. The upper or conical portion of the carbureting passage 4 forms 100 a preliminary mixing chamber 6' in which a preliminary mixture of the air and gas is obtained so that when the mixture reaches the main mixing chamber the mixture will be completed to produce a high explosive 105 charge as will be hereinafter fully described.

Arranged within the carbureting passage 4 at the lower end of the conical portion 6 is a primary Venturi tube 8 into which extends a low speed nozzle 9 having a base portion 10 provided with a well, the walls of which are apertured and register with an

annular groove 11 formed on the circumference of the base portion. The annular groove 11 is adapted to register with a fuel passage 13 formed by a bore extending from 5 a float and fuel chamber 14 which is preferably formed integral with the base section 1 as clearly shown. The float and fuel chamber is provided with a fuel supply 15 controlled by a needle valve 16 carried by 10 the arm of a float 18 which is pivotally mounted within the chamber in the usual manner. A removable cover 19 is provided for closing the float and fuel chamber which is secured thereon in any desired manner 15 and is provided with a spring plunger 20 adapted to engage the float for forcing the same downwardly in order to raise the needle valve off of its seat so as to flood the carburetor if desired.

20 The wall of the conical portion 6 is cut away as shown at 21 into which extends a high speed nozzle 22 formed on the upper end of a fuel pipe 23 extending from the float and fuel chamber, said nozzle being 25 disposed adjacent the contracted portion of a conical tube 24 through which air is adapted to pass in order to draw fuel out of the high speed nozzle so that the additional fuel will be discharged into the preliminary mixing chamber as will be herein- 30 after fully described.

The upper section 2 of the carburetor is provided with a mixing chamber 25 having a horizontally disposed arm 26 terminating 35 in a socket 28 in which is secured a valve stem 29 on which is slidably mounted the bearing sleeve portion 30 of a spider 31 of a hollow conical floating suction-controlled valve 32, the lower portion of which is 40 adapted to cooperate with the seat 7 formed by the upper portion of the lower section 1. The upper portion of the valve 32 is provided with a cylindrical portion 32' adapted to cooperate with an annular seat 33 formed 45 in the bottom of the mixing chamber 25 so as to practically close communication between the auxiliary air chamber 36 formed in the section 1, and the mixing chamber formed in the section 2. The cylindrical portion 32' has a diameter a few thousandths 50 of an inch less than the diameter of the seat 33 formed in the bottom of the mixing chamber. The auxiliary air chamber 36 has its wall cut away above the secondary 55 Venturi tube to produce an auxiliary air inlet 37 through which air passes when the valve is raised in a cylindrical column so as to follow the combustion charge entering the mixing chamber whereby a proper mixture will be obtained at all speeds of the 60 engine.

The valve stem 29 is surrounded by a coil spring 38 above the bearing sleeve of the valve in order to produce a cushioning buffer 65 so as to check the quick action of the

valve. As the valve raises the spring is carried with the same until the spring is brought into engagement with the sleeve 28 which prevents the valve from hammering when the same is raised quickly by the increased suction of the engine. 70

A leather washer 39 is placed on the valve stem 29 below the valve 32 and is held in position by a metal washer 39' slidably mounted on the stem above a transverse pin 40 so as to provide a cushion support for the valve on the stem. 75

In order to provide means for adjusting the position of the suction-controlled valve in respect to its seat, I arrange within a transverse bore 41 a shaft 42 which is provided with a cam 43 at its inner end adapted to engage the washer 39' for raising the valve off of its seat, said shaft being provided with a milled head 44 engaged by a spring plunger 45 for locking the same in adjusted position, and in use the cam is so adjusted that the valve 32 is held slightly raised. 80

It will be seen from the construction thus far described that I have provided a carburetor with a carbureting passage having a main air supply which communicates with a mixing chamber through a hollow suction-controlled valve and with an auxiliary air supply which is normally held closed by a suction-controlled valve so that the secondary or high speed jet will not be brought into operation until the speed of the motor increases beyond the normal speed of travel 100 at which time the high speed jet is uncovered so as to allow the additional fuel to be drawn downwardly around the outside wall of the suction-controlled valve into the preliminary mixing chamber where it 105 mingles with the mixture and is conveyed to the mixing chamber.

By mounting the suction-controlled valve on a fixed valve stem having the cushioning spring arranged above the stem I provide 110 means for preventing the valve from hammering and by having the same supported on a washer which cushions the closing of the valve I provide a suction-controlled valve which is noiseless in operation. 115

The upper section 2 is provided with a throttle chamber 46 surrounded by a heating chamber 47 having an inlet 48 and an outlet 49, the inlet being provided with a butterfly valve 50 carried by a valve stem 51 on which is secured the hub portion 52 of an arm 53. A throttle valve 54 is mounted in the throttle chamber 46 upon a valve stem 55 which extends out through the walls of the section and is provided with an arm 57 connected to the arm 53 by a link 58 so as to open and close the intake to the heating chamber as the throttle is opened and closed. The section 2 is provided with a lug 59 carrying an adjusting screw 60 120

125

130

135

which is adapted to be engaged by the arm 57 for limiting the movement of the throttle valve 54 so that the same can be set so as to only partially close the throttle chamber.

- 5 The heating chamber 47 of the upper section 2 has a solid portion extending obliquely therethrough which is provided with a bore terminating in a recess formed in the throttle chamber above the throttle valve forming a priming nozzle 61. The lower end of the bore is closed by a plug 62 which forms a well to which is connected a fuel supply pipe 64 which extends down into the fuel chamber 14 as shown in Figs. 10 15 2 and 3 for supplying fuel to the priming nozzle. The bore is provided with a conical seat 65 in which is adapted to be seated the conical point 66 of a needle valve 67 which is provided with a head 68 having an annular 20 groove to receive the bifurcated end 69 of an arm 70 fixed on a rock shaft 71 pivotally mounted in a bearing formed in a lug 72 extending outwardly from the section 2 above the auxiliary air inlet. The rock 25 shaft 71 carries an operating arm 73 which may be connected to any suitable controlling means. Surrounding the rock shaft is a coil spring 74 which has one of its ends in engagement with the casting, and the other ends 30 connected to the arm 73 so as to normally hold the needle valve seated. This construction provides spring actuated means for normally holding the priming nozzle closed, and for closing the same after the same has 35 been manipulated from the dash to start the motor.

- When the throttle is in closed position, and it is desired to start the engine by operating the dash control, the needle valve can be adjusted in respect to its seat to allow fuel to be drawn by the suction of the engine into the throttle chamber above the throttle valve so as to prime the motor by allowing pure gasoline to be drawn directly into the cylinders thereof. By the provision of a needle valve for controlling the priming jet I provide a needle valve control which enables me to allow any desired amount of fuel to be drawn directly into the motor for starting the same.

- The main working nozzle 9 is provided with the usual needle valve 75 for controlling the flow of fuel therethrough, and the high speed nozzle is preferably formed with a 55 calibrated jet so that the desired amount of fuel will be drawn through the same by the air passing through the secondary Venturi tube as the suction controlled valve is raised so that the proper proportion of fuel and air 60 will be delivered to the mixing chamber when the motor is running at different rates of speed and by this construction I am able to increase the speed of the motor to which a carburetor is attached quickly without 65 choking the same.

The interior of the floating suction-controlled valve 32 has a shape of a Venturi tube through which passes the partially mixed charges from the low and high speed nozzles so as to increase the velocity of the 70 passage of the charge entering the main mixing chamber.

The operation as herein shown and described is as follows: When the motor to which the carburetor is attached is running 75 at low speed air is taken in through the inlet 5 and passes around and over the main or low speed nozzle 9 and draws fuel therefrom; at the same time a small additional amount of air enters around the floating Venturi 80 tube formed by the floating suction controlled valve from the auxiliary air chamber and the air and mixture is drawn to the mixing chamber through the floating Venturi tube and is delivered to the engine in the 85 usual manner. The suction-controlled valve is adjusted so that the same is held slightly above the seat to provide an annular air inlet so as to allow a small volume of air to pass down around the outer face thereof into the 90 lower portion of the floating venturi formed by the valve. As the speed of the motor is further increased the valve is raised by the increased suction so as to gradually uncover the high speed nozzle and air rushes through 95 the conical tube and draws fuel out of the high speed nozzle which is drawn downwardly into the main air passage and mingles with the air and gas therein and passes up through the floating Venturi tube and is delivered into the mixing chamber.

The length of the cylindrical portion 32' of the floating suction-controlled valve 32 is such that the auxiliary air is not admitted to the main mixing chamber until 105 the suction of the engine has increased to such an extent that the valve is raised approximately one-eighth of an inch which allows the valve to move up and down as the speed of the engine is increased or decreased 110 without supplying additional air to the main mixing chamber, but as the valve rises the additional supply of air to the mixing chamber increases. When the motor has increased its speed to such an extent that the 115 suction within the mixing chamber is sufficient to raise the suction-controlled valve to allow additional air to enter the mixing chamber, the high speed nozzle is uncovered so as to allow air to rush through the secondary Venturi tube, and as the suction within the preliminary mixing chamber or main air passage is so great, the mixture of fuel delivered from the high speed nozzle is drawn downwardly into the preliminary 120 mixing chamber around the lower end of the suction-controlled valve and enters the floating Venturi tube formed thereby where it mixes with the fuel and air entering from the main air and fuel supply and passes up- 125 130

wardly through the floating Venturi tube into the main mixing chamber. As the high speed nozzle is brought into operation by the raising of the valve, the auxiliary air supply allows a cylindrical column of air to enter the main mixing chamber quickly to mix with the preliminary mixture entering the floating Venturi tube formed by the hollow suction-controlled valve so as to obtain a thorough mixture of air and gas, and it will be seen that by the construction herein shown and described a central volume of air and fuel is drawn through the floating Venturi tube into the main mixing chamber surrounded by a cylindrical column of air from the auxiliary air chamber.

In practice I have found that a small amount of fuel will be drawn from the high speed nozzle before the valve has raised to such an extent as to open the additional air supply to the main mixing chamber, as when the valve is raised slightly a small amount of air will pass through the secondary Venturi tube over the high speed nozzle so as to supply a slight additional amount of fuel at an intermediate speed of the motor, and in fact, the construction of the parts are such that the carburetor is sensitive to a slight increase of speed; that is, an additional amount of air and fuel is proportionally admitted as the speed of the motor is gradually increased, and when the motor has reached a high speed, the nozzles are open to the full force of the air from the Venturi tubes so as to supply the motor with ample fuel, and at the same time the auxiliary air supplies are brought into operation so that the proper mixture is obtained on all speeds of the motor.

40 In the operation of the priming jet in starting the motor fuel will be drawn directly from the bowl into the throttle chamber above the throttle valve so that the suction of the engine will draw fuel or mixture into the cylinders thereof in order to allow the same to start quickly.

From the foregoing description it will be seen that I have provided a carburetor with a priming nozzle for starting the motor to which it is attached, a working nozzle for supplying a mixture to the motor when running at low or high speed and with a high speed nozzle for supplying to the mixture produced by the low speed nozzle an additional supply of fuel and air in order to obtain the proper mixture in all speeds of the engine.

I claim:

1. In a carburetor, a main fuel nozzle, an air passage having a main air inlet and beyond said fuel nozzle superposed secondary air inlets, the bottom secondary air inlet

being of conical form, a high speed nozzle arranged at the contracted end of said conical secondary air inlet and a suction operated tubular valve controlling said secondary air inlet and fuel nozzle, and serving to conduct the mixture of air and fuel from said nozzles to a point beyond the upper secondary air inlet.

2. In a carburetor, a main fuel nozzle, an air passage having a main air inlet and beyond said fuel nozzle two separated secondary air inlets, a high speed fuel nozzle arranged in alignment with the air current from the secondary air inlet which is nearest the main fuel nozzle and a suction controlled tubular valve controlling successively said secondary air inlets and serving to conduct the mixture of air and fuel from said nozzles, the secondary air inlet associated with the high speed nozzle being the first to open.

3. In a carburetor having a carbureting passage extending therethrough provided with a main air inlet at its lower end and a fuel nozzle disposed therein, said carbureting passage having separated secondary air inlets arranged above the main fuel nozzle, one of said secondary air inlets having a conical passage, a fuel nozzle disposed in alignment with the end of said conical passage and a suction controlled valve of tubular form controlling successively said secondary air inlets and serving to conduct the mixture of air and fuel from said nozzles, one of said secondary air inlets delivering a hollow column of air to said carbureting passage around the fuel and air passing through said tubular suction controlled valve.

4. In a carburetor having a carbureting passage extending therethrough provided with a main air inlet at its lower end and a main fuel nozzle, separated secondary air inlets arranged above said main fuel nozzle, a high speed nozzle arranged in alignment with the secondary air inlet disposed closest to the main fuel nozzle, a tubular suction controlled valve controlling successively said secondary air inlets and arranged to receive and conduct the mixture of air and fuel from said nozzles, the secondary air inlet arranged the farthest away from said main fuel nozzle being arranged to deliver a hollow column of air around the mixture of fuel and air passing through said tubular suction controlled valve.

In testimony whereof I hereunto affix my signature in the presence of a witness.

BURT N. PIERCE.
